(57) **CLAIM**

The ornamental design for a customizable caddy, as shown and described.

DESCRIPTION

FIG. 1 is a perspective view of a customizable caddy showing our new design;

FIG. 2 is a right side view thereof;

FIG. 3 is a left side view thereof;

FIG. 4 is a front view of thereof, the rear being a mirror image;

FIG. 5 is a front view thereof, the locking bracket removed for ease of illustration;

FIG. 6 is a top view thereof as assembled in FIGS. 1-4; and, FIG. 7 is a bottom view thereof.

The broken line showing in FIG. 7 is included for the purpose of illustrating unclaimed subject matter and forms no part of the claimed design.

1 Claim, 7 Drawing Sheets
